UNITED STATES PATENT OFFICE.

LAMBERT J. BORDO, OF ROSLYN, PENNSYLVANIA.

BOILER-PROTECTING DEVICE.

1,306,167.

Specification of Letters Patent. Patented June 10, 1919.

Application filed February 6, 1918. Serial No. 215,594.

To all whom it may concern:

Be it known that I, LAMBERT J. BORDO, a citizen of the United States of America, and resident of Roslyn, in the county of Montgomery and State of Pennsylvania, have invented a certain new and useful Improvement in Boiler-Protecting Devices, of which the following is a true and exact description, reference being had to the accompanying drawings, which form a part thereof.

My present invention has for its object to provide simple and effective means for automatically indicating a dangerous low water condition in boilers. In carrying out my invention I employ a fusible plug which forms a part of the wall of a chamber communicating with the interior of the boiler, but which is normally insulated against the internal temperature of the boiler, but is subjected to steam temperature of the boiler immediately on a depression of the water level in the boiler to a predetermined minimum. The melting of the fusible plug, which occurs when the latter is exposed to the steam temperature of the boiler, permits the escape of steam from the boiler and thereby indicates the dangerous low water condition of the boiler.

The various features of novelty which characterize my invention are pointed out with particularity in the claims annexed to and forming a part of this specification. For a better understanding of the invention, however, and the advantages possessed by it reference should be had to the accompanying drawings and descriptive matter in which I have illustrated and described a preferred embodiment of my invention.

Of the drawings:

40 Figure 1 is an elevation of a portion of a boiler equipped with my invention.

Fig. 2 is an elevation at right angles to Fig. 1, with parts shown in section, and

45 Fig. 3 is a sectional elevation of the fuse plug.

In the drawings, A represents a boiler to which my improvement is applied. My improved safety device E comprises a chambered casing, the interior of which is connected at its lower end to the interior of the boiler below the normal water level therein. Advantageously, as shown, this casing is associated with a water level indicating gage B connected to the boiler at top and bottom by valved connections C and C'. In this mode of utilizing my invention I connect the

chambered casing E to the valve connection C by which the lower end of the gage B is connected to the boiler. In the particular construction illustrated this is accomplished by forming the casing of the valved connection C with a threaded lateral aperture C² into which I screw one end of a pipe elbow D, which may be regarded as forming the lower portion of the chambered casing E. 65 Into the other end of the elbow D, which is turned upward, I screw the lower end of a pipe section which at its upper end is connected to a casing part F threaded on the upper end of the pipe section. Threaded 70 to the upper end of the casing part F is the casing part G which is formed at its upper end with a threaded aperture receiving a hollow externally threaded plug H, in the bore of which is cast, or otherwise secured, 75 a core or plug I of some suitable alloy fusing at a temperature less than the steam temperature normally prevailing in the boiler A. A vent connection J is threaded into the casing member G and is normally closed by the cock K. Axially disposed in but not filling the outer pipe section is a pipe L, secured at its upper end in a spider-like portion R' of the casing member F. The lower end of the pipe L projects down into the 85 elbow D. As shown, the casing element E is secured in its upright position by being passed through apertured ears B' formed on the body of the gage B.

With the normal range of boiler water 90 level in which the water level is visible through the gage window B², the casing element E, which is in communication with the interior of the boiler through the elbow D and the valve casing C', is filled with 95 water. The water then filling the interior of the tubular element E will be at a temperature substantially lower than the steam temperature of the boiler and but little above atmospheric temperature on account 100 of the poor heat conductivity of the water and the heat radiation from the valve casing C' and the casing element. When the water level in the boiler becomes so low, however, that steam passes through the 105 valved connection C into the elbow D, the water in the casing element E immediately drains out of the latter through the inner pipe L, which forms, in effect, the long leg of a siphon, the short leg of which is the annular space surrounding the pipe L. 110

In consequence, the fusible plug I is sub-

jected to the steam temperature in the boiler almost instantly after the fall in the boiler water level permits steam to enter the elbow D. When exposed to the steam temperature the fusible plug I melts, thus permitting steam to blow out through the axial passage in the hollow plug H. This discharging jet of steam gives a very effective and readily discernible indication of the dangerous low water condition of the boiler. The escape of steam may be stopped, of course, by closing the valved gage connections C and C', and the plug H may then be replaced by another having its fusible core plug I intact. After the water level in the boiler is restored and the valve connections C and C' are opened the casing element E may be again completely filled with water by opening the cock K long enough to permit the escape of any air which may have accumulated within the tubular element. The provision of the siphon discharge from the casing element E, obtained in the particular construction illustrated, by providing the pipe L in but not filling the outer pipe section portion of the member E insures a speedy exposure of the fusible plug to the steam temperature when steam is admitted to the lower end of the shorter leg of the siphon. If this siphon connection were not provided there would be a tendency for the casing element E to remain filled with water after the water level has fallen low enough to permit the steam to pass into the pipe elbow.

My improvement in the form disclosed was especially devised for use in connection with locomotive and marine boilers where it is of special utility. Its use is not restricted, however, to such boilers. There is an especial advantage in employing my improved safety device in conjunction with a water level gage in the general manner disclosed, as this facilitates the ready application of the device to a boiler and makes unnecessary any special pipe connection to the boiler proper or any special valve or valves for disconnecting the device from the boiler when it is necessary to renew the fusible plug I. The association of the device with a gage in the manner disclosed also makes it readily possible to get the device far

enough away from the boiler to keep the normal temperature of the device desirably low without using the additional space in 55 the locomotive cab or engine room which would be required if the gage and device were separately attached to the boiler.

While in accordance with the provisions of the statutes I have illustrated and described the best form of my invention now known to me, it will be apparent to those skilled in the art that changes may be made in the form of my invention without departing from its spirit, and that some features of my invention may sometimes be used to advantage without a corresponding use of other features of the invention.

Having now described my invention, what I claim as new and desire to secure by Letters Patent, is:

1. A low water indicating device for boilers comprising a chambered casing adapted to be connected at its lower end to the water space of the boiler, and provided at its upper end with a wall portion formed of material melting at a temperature lower than the normal steam temperature of the boiler, said casing being formed with two passages leading from the top of said casing to different levels adjacent the bottom thereof and uniting to form a siphon discharge from said chamber for the water contained in the upper portion thereof, when a fall in boiler water level permits steam to enter the lower end of said chamber.

2. A low water indicating device for boilers comprising a chambered casing adapted to be connected at its lower end to the water space of the boiler, and provided at its upper end with a wall portion formed of material melting at a temperature lower than the normal steam temperature of the boiler, said casing being formed with two passages leading from the top of said casing to different levels adjacent the bottom thereof and uniting to form a siphon discharge from said chamber for the water contained in the upper portion thereof, when a fall in boiler water level permits steam to enter the lower end of said chamber, and a valved air vent connected to the upper end of said chambered casing.

LAMBERT J. BORDO.
